Primary Examiner—Stella Reid*Assistant Examiner*—Eric M. Watterson*Attorney, Agent, or Firm*—Hugh E. Smith[57] **CLAIM**

The ornamental design for a boat fuel delivery apparatus, as shown and described.

DESCRIPTION

FIG. 1 is a front elevational view of the boat fuel delivery apparatus showing my new design;
FIG. 2 is a rear elevational view thereof;
FIG. 3 is a left side elevational view thereof;
FIG. 4 is a right side elevational view thereof;
FIG. 5 is a top plan view thereof; and,
FIG. 6 is a bottom plan view thereof.

FIG. 1

FIG. 2

*FIG. 3**FIG. 4**FIG. 5*

FIG. 6
